UNITED STATES PATENT OFFICE.

THEODORE F. UHLEMANN, OF GLEN MORRIS, NEW YORK, ASSIGNOR TO NICHOLAS POWER COMPANY, INC., OF NEW YORK, N. Y., A CORPORATION OF DELAWARE.

TENSION DEVICE FOR MOVING-PICTURE MACHINES.

Application filed July 2, 1920. Serial No. 393,604.

To all whom it may concern:

Be it known that I, THEODORE F. UHLEMANN, a citizen of the United States, and a resident of Glen Morris, Queens County, 5 Long Island, New York, have invented new and useful Improvements in Tension Devices for Moving-Picture Machines, of which the following is a specification.

This invention relates to aperture gates 10 for motion picture machines and has for its object to provide a gate adapted to support the tension shoes for the film at the aperture and also the film-holding roller for the intermittent sprocket to thereby facilitate the 15 rapid threading of the machine.

A further object of the invention is to provide a gate of this character in which the action of the sprocket roller is controlled by the movement of the gate in such manner 20 that the sprocket roller is released from the sprocket before the gate can be opened and is closed against the sprocket only after the gate is fully shut, by which arrangement the film is threaded on to the intermittent 25 sprocket by merely closing the gate against the film. To this end the tension shoes carried by the gate extend to a point near the sprocket and serve to properly position the film so that when the sprocket roller is released 30 the perforated margins are pressed against the sprocket teeth to be caught by the teeth when the movement of the sprocket begins.

A further object of the invention is to provide a novel latching device for the gate arranged to engage and lock automatically 35 when the gate is closed, the lock being designed to afford much more positive fastening of the gate than can be had with the ordinary bevel-edge spring bolt usually employed in self-engaging locks.

In the accompanying drawings I have shown a preferred arrangement of my improved tension device and also certain modifications which will be hereinafter described. 45

In the said drawings,

Figure 1 is a side elevation of a moving picture machine showing my improved gate applied to an enclosed machine;

Fig. 2 is a rear elevation of the structure shown in Fig. 1;

Fig. 3 is a plan view of my improved gate; Fig. 4 is a horizontal sectional view taken

approximately midway of my improved gate; and

Figs. 5 and 6 are detail views showing the use of a film-holding shoe instead of a roller for the sprocket.

Referring to the drawings, particularly Figs. 1 and 2, 1 indicates the frame of the machine, which frame comprises a vertical web on which the three film-feeding sprockets are supported in the usual manner. The intermittent sprocket 2 is positioned immediately below the position of the ray chute 3 with the periphery of the sprocket lying in the plane of the film-guiding surface of the aperture plate 4 fixed to the rear end of the ray chute.

Hinged to the frame in a position to close 70 against the aperture plate is a gate 5, the lower edge of the gate extending below the aperture plate and to the rear of the sprocket. The gate is of course provided with an aperture corresponding to the one 75 in the plate to permit the passage of light to the film and on each side of the aperture it is provided with film-guiding shoes 6 supported by cross bars above and below the aperture and designed to engage the 80 margins of the film to hold the film taut at the aperture.

Each shoe 6 is provided at its middle point with a tongue 7 which projects through a hole in the gate in position to be engaged 85 by the presser spring 8 which is attached to the back of the gate, the tongue being provided with a flange at its end to prevent the accidental displacement of the shoes when the gate is open.

Each spring 8 consists of a single spring bow with its convex side turned toward the gate arranged to press at its middle point against the end of the tongue 7 as shown in Fig. 1. The springs are supported so that 90 they may be quickly withdrawn and a new one replaced in case of breakage. To this end the lower ends of the springs are supported in square sockets 10 formed in a bracket 9 attached to the back of the gate 100 near the lower edge. The upper ends of the springs are free but extend under downwardly projecting ears 11 on the lower edge of the rocking spring adjusting member 12 supported at the top of the gate. The member 12 consists of a block pivoted near its

lower edge on a transverse pivot pin 13 extending across the back of the gate between edge flanges 11^b, the ears 11 of the block being recessed to receive the free ends of the 5 springs. By this arrangement the reaction of the springs tends to turn the block on its pivot, forcing the upper edge of the block toward the gate and against an adjusting screw 14 which is threaded through the 10 flange of the gate. The end of the block adjacent the adjusting screw is beveled off on its inner face as shown so that the end of the screw comes against the inclined face of the block whereby the transverse adjustment of the screw will tend to turn the block on its pivot to thereby regulate the tension of the springs 8.

A frame 15 is pivoted to the lower end of the gate for supporting the sprocket-engaging roller 16 in position to engage the sprocket at a point below its axis to thereby maintain the desired number of holes in engagement with the teeth of the sprocket. The frame 15 is pivoted to the gate and comprises a pair of downwardly extending arms supporting the pivots of the roller, the pivots of the frame preferably consisting of screws set in the frame with their pointed ends in sockets formed in the ears at the edges of 30 the gate whereby the frame may be readily detached for replacement. One of the side arms of the frame is extended upwardly beyond its pivot and at a point above the pivot is engaged by a spring 17 set in a socket on 35 the gate to thereby turn the frame on its pivot to force the roller toward the sprocket. The movement of the roller toward the sprocket is limited by a stop-screw 18 set in the back of the gate in a lug overlying the 40 arm whereby the movement of the frame may be adjusted so that the grooves in the ends of the roller 16 will hold the film on the teeth of the sprocket but not apply any undue pressure to the film.

45 To hold the gate in closed position I provide a latch 19 consisting of a bar supported for vertical movement along the edge of the gate by means of screws 20 working in slots in the bar. The upper end of the bar is 50 turned out to provide a thumb-piece to facilitate the lifting of the bar and projecting from the edge of the bar is a hook 21 designed when the gate is closed to engage over a pin 22 set in the edge of the aperture plate.

55 The lower end of the latch 19 is shaped to provide a deep hook 23 open to the rear of the gate to receive a pin 24 in the end of the long side arm of the frame 15. The point of the hook is beveled as shown to provide a 60 cam surface for engaging the pin when the latch is raised, to thereby turn the frame 15 on its pivots and withdraw the roller from the engagement with the sprocket before the latch clears the pin 22. By this arrangement the roller is fully withdrawn from the

sprocket before the gate can be opened and the gate must be closed against against the film before the roller can be released, thereby avoiding all possible danger of tearing the film on the sprocket teeth.

70

The latch bar 19 is normally held in elevated position when the gate is opened only by the pressure of the pin 24 against the side of the hook 23 under the tension of the spring 17, the latch bar being otherwise 75 freely slideable on its guide screws so as to drop by gravity to its lowermost position when the pressure of the pin against the hook is relieved. This construction is provided in order that the operator may shut 80 and latch the gate with one hand to thereby leave one hand free to hold the film in place when the gate is shut. The operator frees the latch bar by simply engaging the gate, when he closes it, along the arm of the frame 85 15. The tension of the spring 17 is such that when the gate is closed against the film the guide shoes will be placed under tension and the hook of the latch will be advanced beyond the pin 22 before the pin 24 releases 90 the hook 23 and allows the latch bar to drop. The gate will thus always be latched if the operator takes hold of the arm when closing the gate.

In addition to facilitating the rapid and 95 correct threading of the machine the attachment of the sprocket roller to the gate permits the film guides to extend almost to the periphery of the sprocket, thereby greatly lessening the tendency of the film to "buckle". 100 Between the sprocket and the aperture when the machine is run at high speed, and without undue pressure applied to the guide shoes. My improved latch has the advantage of always holding the gate closed to the 105 same position, due to the flat surface of the hook which engages the pin. In ordinary spring latches having bolts with beveled ends which are forced back by the engagement of the bolt with its socket, the unavoidable wear of the parts produces an undesirable lost motion in the gate, particularly if the spring bolt is strong enough to insure positive latching.

110 Instead of using a roller for holding the film against the sprocket, I may employ a shoe 30 such as shown in Figs. 5 and 6, the shoe being preferred by some operators for the reason that it holds the film in engagement with a greater number of the sprocket 115 teeth. The shoe may be fixed in the frame 15 but is preferably loosely pivoted in the frame by the bayonet joint 32 to permit the shoe to adjust itself to the sprocket under the pressure of a spring 33.

120 My improved tension mechanism is particularly applicable to machines in which the framing is accomplished without movement of either the lower sprocket or the aperture plate, and is also applicable to the style 130

of framing described in my co-pending application Serial No. 386,143 filed June 3, 1920, in which the sprocket is adjusted relatively to the aperture plate but with the gate and film plate adjustable with the sprocket, and I have disclosed my improved tension device in that application.

I claim:

1. In a tension device for moving picture machines, the combination of an aperture plate having a film-guiding surface, a co-operating member mounted for movement toward and from said surface, tension shoes carried by said member engaging the film at the aperture, an intermittent sprocket adjacent said aperture plate for advancing the film through the machine, a guide for holding the film in contact with the sprocket, said guide being supported on said co-operating member, and means for holding said guide out of engagement with the sprocket until said gate is moved into closed position and subsequently causing it to engage the sprocket.
2. In a tension device for moving picture machines; the combination of an aperture plate having a film guiding surface, a co-operating member mounted for movement toward and from said surface, tension shoes carried by said member engaging the film at the aperture, an intermittent sprocket adjacent said aperture plate for advancing the film through the machine, a guide for holding the film in contact with the sprocket, said guide being supported on said co-operating member and mounted for movement independent of said member, and means for causing the movement of said guide into engagement with said sprocket after the film has been engaged by the tension shoes.
3. In a moving picture machine, the combination of an aperture plate, a gate for maintaining the film in contact with the aperture plate, a latch for said gate, an intermittent sprocket adjacent the aperture plate, a film guide for maintaining the film in contact with the sprocket, said guide being mounted on said gate for movement toward and from the sprocket independent of the movement of the gate, and connections between said latch and said guide for controlling the movement of the guide from the latch.
4. In a moving picture machine, the combination of an aperture plate, a gate for maintaining the film in contact with the aperture plate, a latch for said gate, an intermittent sprocket adjacent the aperture plate, a film guide for maintaining the film in contact with the sprocket, said guide being mounted on said gate for movement toward and from the sprocket independent of the movement of the gate, and means controlled by the movement of the latch for causing said guide to engage the film on the

sprocket when the latch moves into the latching position and to withdraw said guide from the sprocket when the latch is moved to open position.

5. In a moving picture machine, the combination of an aperture plate, a gate having means for holding the film in contact with the aperture, a latch for said gate comprising a locking member movable into locking position only after the closing movement of the gate is completed, means for holding said locking member in unlocked position when the gate is open, said means being designed to cause the release of the said locking member when the gate is stopped upon engaging the aperture plate in its closing movement.

6. In a moving picture machine, the combination of an aperture plate, a gate for maintaining the film in engagement with said plate, a latch for said gate, an intermittent sprocket for advancing the film past the aperture, a film guide for the sprocket supported on said gate for movement independent thereof, and operative connections between said gate, said film guide and said latch and means for simultaneously holding said latch and guide in open position, comprising interengaging portions provided on said members, said holding means being releasable to effect closing of the latch and shifting of the guide into engagement with the film at the completion of the closing movement of the gate.

7. In a moving picture machine, the combination of a film gate, tension shoes carried by said gate, a latch for said gate consisting of a latch bar mounted for free movement having a hook which assumes locking position on the movement of said bar, a sprocket adjacent said gate, a film guide for said sprocket pivoted on said gate for independent movement toward and from the sprocket, a spring for holding said guide normally pressed toward the sprocket, and cooperating portions provided on said guide and said latch bar maintained in interengaged position by said spring for simultaneously holding said parts in inoperative relation, said latch being released by pressure on said guide when the gate reaches its closed position.

8. A tension device for moving picture machines comprising tension shoes for engaging the film on each side of the aperture, an adjustable support for said shoes, said shoes being loosely mounted in said support for free movement toward and from the film, springs for said shoes comprising spring metal bows attached to said support at one end and engaging said shoes at their middle portion, and means for adjusting the pressure of said shoes comprising a member overlying the free ends of said springs and adjustable toward and from the support.

- 4
9. A tension device for moving picture machines comprising tension shoes for engaging the film on each side of the aperture, an adjustable support for said shoes, said shoes being loosely mounted in said support for free movement toward and from the film, springs for said shoes comprising spring metal bows attached to said support at one end and engaging said shoes at their middle portion, and means for adjusting the pressure of said shoes comprising a member pivoted to said support at one side of said member and engaging the free ends of said springs, and an adjusting screw for turning said member on its pivot against the pressure of said springs. 15

Signed at New York, in the county of New York and State of New York this 2nd day of June, 1920.

THEODORE F. UHLEMANN.
